UNITED STATES PATENT OFFICE.

WALTER JOHN KIMBER, OF OTTAWA, ONTARIO, CANADA.

BRICKLAYER'S TOOL.

Application filed October 9, 1922. Serial No. 593,355.

To all whom it may concern:

Be it known that I, WALTER JOHN KIMBER, a subject of the King of Great Britain, and a resident of the city of Ottawa, in the 5 Province of Ontario and Dominion of Canada, have invented certain new and useful Improvements in Bricklayers' Tools, of which the following is a specification.

This invention relates to improvements in 10 bricklayers' tools, and more particularly to convertible and adjustable double jointers and joint-rakers, and the objects of the invention are to provide a jointing and raking tool which will enable the operator to accomplish double the amount of work in the 15 same period of time and in a more uniform and efficient manner than with any tool or improvised instrument hitherto used for jointing and raking out brick-work.

With these and other objects in view, the 20 invention consists essentially in the novel construction and arrangement of the several parts hereinafter described in the present specification and illustrated by the accompanying drawings that form part of the 25 same.

Referring to the drawings, in which like characters of reference indicate corresponding parts in all the figures, and in which:

30 Figure 1 is a plan view of the tool, assembled as a double raker or jointer.

Figure 2 is a plan view of the tool in single form, making a separate tool for use on cross or perpendicular joints.

35 Figure 3 is a side elevation, showing the raker-blades adjusted ready for use.

Figure 4 is a similar view, partly in section.

Figure 5 is a section on the line 5—5 of 40 Figure 1.

Figure 6 is a plan view of the parts of the tool, separated.

Figure 7 is a perspective detail of the raker-blade.

45 Figure 8 is a plan view of the underside of the jointer-blade.

Figure 9 is a side elevation of the jointer-blade.

50 Figure 10 are sectional details of the jointer-blade, showing variations in form.

Figure 11 are plan views of the front of the raker-blade, showing variations in width and depth of claws.

55 In the drawings:

A is the tool as a whole consisting of two parts 10 and 11 constructed of suitable ma-

terial, preferably as here shown of steel, the part 10 being substantially L-shaped and the part 11 being straight. The part 10 is provided with a forked lug 12 designed to slid- 60 ably engage with a slot 13 in the part 11 and to be fixedly secured therein by means of a thumb screw 14 extending through an orifice 15 in said part 11, and then extending be- 65 tween the prongs of the lug 12.

By the above described means, it will be seen that the parts of the tool are adapted to be adjustably connected at one end by means of the lug 12 in one part engaging with an opening or slot in the other. By this 70 means also the parts are adapted to be moved wide apart or to be closed together as far as the construction of the parts will permit which, on account of one of them being L-shaped, will mean that when at their nearest 75 point of contact they will extend horizontally in spaced relationship to one another as shown in the different figures, particularly Figure 1.

The outer ends of the parts 10 and 11 are 80 provided with slots 17 and 18 designed to receive therein the blades 19 and 20 designed to slidably operate in said slots and to be fixedly secured therein by thumb screw means 21. These blades 19 and 20 are of 85 two kinds; raker and jointer blades, the raker-blades being formed with claws 22 on the lower side adapted to rake out the brickwork, and an upper claw 23 designed to act as a gauge on arris of bricks at bed joints, while the jointer-blades are formed with a jointer 25, and made with a small lift 26 by which means the gauge part of the jointer will be brought on a level with the 90 face of the roller means 27 hereinafter more fully described. The inner ends of these blades are formed with orifices 24 to engage with the thumb screw means 21.

The raker-blades are particularly illustrated in Figure 7, and the jointer-blades in 100 Figures 8 and 9.

For the more efficient operation of the tool, I provide a transversely extending roller 27 suitably mounted on the underside of the body portions in hubs 29 and 30. 31 is a handle for the tool adapted to be dovetailed in a slot 32 and made fast therein by thumb screw means 33.

From the foregoing it will be seen that 110 the tool can be easily used in double formation as a raking tool, as illustrated in Figure 1, or in single formation as shown in Figure

2 as a jointing tool, by simply changing the blades. These blades are also provided with raking claws of various width and depths, and being interchangeable can be adapted to 5 any particular kind of work. This remark also applies to the jointer-blades in which the different forms of the jointer are illustrated in Figure 10, and the different forms of the raker claws being illustrated in 10 Figure 11.

From the foregoing, it will be seen that I have provided an efficient and simply constructed tool to take the place of makeshifts in the shape of pieces of steel, nails and 15 otherwise now used by bricklayers for jointing and raking brickwork, and also a tool that can be turned out economically in large quantities.

It may also be mentioned that the roller 20 is interchangeable as well as the blades, and can be varied in length according to the width apart to which the portions of the tool are required to be operated. In joining the tool in double formation, instead of having the lugs on the inner side 25 of one portion, as shown in Figure 5, they can be applied to both sides extending outwardly, so that the portions 10 and 11 can slide outwardly thereon. In other words, 30 instead of the horse-shoe shaped lug being on the inside and extending inwardly, as shown in Figure 5, it can be adapted to extend outwardly in combination with a similar lug on the other portion of the tool, 35 thus enabling the two sides 10 and 11 to be moved outwardly as required.

As many changes could be made in the above construction and many apparently 40 widely different embodiments of my invention within the scope of the claims, constructed without departing from the spirit or scope thereof, it is intended that all matter contained in the accompanying specification and drawings shall be interpreted as 45 illustrative and not in a limiting sense.

What I claim as my invention is:

1. A jointing and raking tool for bricklayers comprising a body portion provided with a handle and having a slot therein adjacent to said handle, a slot in the outer 50 end of said body portion adapted to slidably engage with interchangeable blades formed with raking or jointing means, thumb screw means for fixedly securing the blades in 55 said slot, similar means for holding the tool

handle in position, and interchangeable roller means beneath said body portion.

2. A jointing and raking tool of the class described comprising a body portion formed in two parts adapted to slidably engage 60 one another in spaced relationship, slots in the ends of said portions and raking and jointing blades adapted to slidably engage with said slots, screw means for fixedly securing the blades in position, similar means 65 for adjusting and holding the body portions in position, and roller means beneath the body portion operatively mounted in hubs on said parts, and handle means for operating the tool. 70

3. A jointing and raking tool of the character described comprising a body portion formed in two parts slidably connected in spaced relationship to one another, means for fixedly holding the parts together, and 75 means in the parts adapted to adjustably engage with raking and jointer blades, means for retaining said blades in adjusted position, and roller means for said parts adjustably mounted on the underside of the 80 parts.

4. A bricklayer's tool of the character described comprising a body portion formed in two detachable parts adapted to be operated singly in spaced relationship to one 85 another, blade retaining means in said parts, and interchangeable raker and jointer blades carried by said parts, means for adjusting said blades, and roller means suitably mounted in hubs on the underside of 90 said parts.

5. In a device of the character described and in combination, an engaging member and a receiving member adapted to adjustably engage with one another and in spaced 95 relationship, means for retaining said members in adjusted position, detachably secured handle operating means for said members, blade carrying members in said members, interchangeable raker and jointer blades adjustably mounted in said blade carrying 100 means, and means for retaining the blades fixedly in position when adjusted, interchangeable roller means carried in hubs on the underside of said members.

In witness whereof I have hereunto set my hand in the presence of a witness.

WALTER JOHN KIMBER.

Witness:

W. T. CUFF QUIN.
